(57) **CLAIM**

The ornamental design for a window for a computer display screen, as shown and described.

DESCRIPTION

The file of this patent contains at least one drawing executed in color. Copies of this patent with color drawing(s) will be provided by the Patent and Trademark Office upon request and payment of the necessary fee.

FIG. 1 is a front view of a window for a computer display screen;

FIG. 2 is a front view of a second embodiment thereof; FIG. 3 is a front view of a third embodiment thereof; and, FIG. 4 is a front view of a fourth embodiment thereof.

The broken line drawing of a window border in figure views 1 through 4 is for illustrative purposes only and forms no part of the claimed design.
